HARRY KAUFMAN AND SAMUEL SCIENS, OF HAMMOND, INDIANA.

RADIATOR.

1,355,835.

Specification of Letters Patent.

Patented Oct. 19, 1920.

Application filed August 23, 1919. Serial No. 319,305.

To all whom it may concern:

Be it known that we, HARRY KAUFMAN and SAMUEL SCIENS, citizens of the United States, residing at Hammond, in the county 5 of Lake and State of Indiana, have invented a new and useful Improvement in Radiators, of which the following is a specification.

Our invention relates to an improved 10 form of radiators for use on motor vehicles in which the water passages are formed between adjacent radiating units constructed from thin metal such as sheet brass, by forming a continuous strip of the metal 15 into rounded corrugations transversely of the strip, equally spaced, alternate ones of the corrugations on one side of the strip being extended to form spacing members to provide air passages through the completed 20 radiator core. The corrugations adjacent the spacing members are flattened between the edges of the strip in the direction the spacing members extend to form water passages in the completed core, extending vertically 25 without interruption or change of direction from top to bottom of the core.

A metal strip thus formed is folded adjacent one of the spacing members to contain the spacing members between the 30 folded portions of the strip, in which position the spacing members alternate with each other and reinforce all of the inwardly projecting corrugations of the unit. A second unit of the kind described is placed 35 against the side of the first unit in reversed relation, that is to say the top of the second unit is the same as the bottom of the first unit and the right hand side of the second unit is the same as the left hand side of the 40 first unit. In this position a continuous water tube is formed between the units extending vertically and the corrugations of the units fit each other so closely that when the core is assembled by placing the desired 45 number of units together, the edges of adjacent units may readily be secured together by dipping them in melted solder which seals the edges of the water tubes.

Our invention will best be understood by 50 reference to the accompanying drawings, showing a preferred embodiment thereof, in which—

Figure 1 is a perspective view of several units in assembled relation,

Fig. 2 is a sectional view of the parts shown in Fig. 1 taken along the line 2—2,

Fig. 3 is an enlarged end view of several units in assembled relation, and

Fig. 4 is a side elevation of a portion of one of the units shown in Fig. 3, 60

Similar numerals refer to similar parts throughout the several views.

As shown in the drawings and particularly Fig. 3, a strip of thin sheet metal such as brass is formed into a plurality of corrugations 10, 11, 12, 13, this series of corrugations being repeated throughout the whole length of the strip. The corrugation 10 projects to the left of the plane of the original strip, for the position of the parts 65 shown in Fig. 3, and has a rounded outline, as have the similarly projecting corrugation 12, and the oppositely projecting corrugation 13. The corrugation 11 extends oppositely to the corrugations 10 and 12, 70 and is continued in triangular form beyond the crest of the corrugation 13 to form a spacing and reinforcing member. The corrugations described extend from edge to edge of the strip in which they are formed. 75 The mid portions of the corrugations 10 and 12 are flattened as indicated in Fig. 4 at 10^a, 12^a, beginning a short distance from either edge of the strip, the flattening being toward the corrugations 11 and 13; the ends 80 of the corrugations 10 and 12 are not flattened but retain the same general form as the corrugations 13 for a sufficient distance from the edge of the strip to facilitate soldering or brazing adjacent units together 85 to form a complete radiator core. 90

A strip corrugated as described is folded, preferably immediately adjacent a corrugation 13, so that the corrugations 11 extend toward each other. The strip is cut of 95 proper length to form a unit of the height of the radiator core and the cut ends are overlapped as indicated at 14. In this position it will be noted that each corrugation 11 rests against a corrugation 13 on the 100 other side of the unit, these parts being held together when the core is brazed or soldered.

A second unit is then formed in the same manner from the same corrugated strip and placed in reversed relation against the first 105 unit, so that its folded portion is down and its lapped portion is uppermost, and its corrugations 10, 11, 12, 13, closely engage the corrugations 11, 10, 13 and 12 respectively. It will be noted that for this relation of the units, the flattened portions 10^a and 12^a occur at each corrugation from top 110

to bottom of the units, alternate ones of said flattened portions being on one unit and intermediate ones being on the other unit. The flattened portions are somewhat deeper than the corrugations in which they are formed and as a result, an uninterrupted passageway for water flow is formed between the units closed at its edges by the engagement of the corrugations of the two units as above referred to.

As more clearly shown in Fig. 2 the water passage thus formed is not of uniform cross section throughout its length, but on the other hand, is of increased cross section at the midportion vertically of each flattened portion of the corrugations, and that this increase is greater at the corrugations than at the other corrugations. Thus, while the water has an uninterrupted path vertically and no horizontally disposed surfaces to collect dirt and foreign matter, it does not flow through the passage with such velocity as to prevent radiation of its heat; as the water enters each portion of increased cross section its flow is somewhat retarded by the slight eddy currents or whirls set up and this affords an ample time interval of contact of the water with the radiating surfaces to insure efficient cooling of the water.

The radiating surface of the air passages is relatively great as a result of the corrugated construction of the units. Furthermore, the ends of the flattened portions, project an appreciable distance into the air passages, and since said ends are oblique longitudinally of the flattened portions, the effect is that air will enter with practically no resistance, the thin edged front ends of the air passages and strike directly against the inwardly projecting ends of said flattened portions, after which the air in any air passage enters a portion of decreased cross section between said flattened portions and its velocity is increased, thus securing more effective cooling of the water than if the air flowed through passages of uniform cross section.

The complete core is formed by assembling enough units in the manner above described to give the desired width of core, each unit being of a length equal to the height of the core. Alternate units occupy the position described above for the first unit, and the intermediate units occupy the position described above for the second unit. The units thus assembled are held closely together by any suitable clamping means, and the adjacent edges of the units are secured together by brazing or soldering, by tipping or otherwise, which results in closing the edges of the water tubes including the open places in the end of the corrugations 11, since in practice these are small enough to be readily closed as described, and at the same time each corrugation 11

is securely fastened to the adjacent corrugation on the other side of the same unit, thus making a strong rigid core.

While we have shown our invention in the particular embodiment above described, it will be understood that we do not limit ourselves to this exact construction as we may employ equivalents known to the art at the time of the filing of this application without departing from the scope of the appended claims.

What we claim is:

1. In a radiator, the combination of a plurality of similar units assembled in reversed relation to form water passages between them, each unit comprising a strip of thin sheet metal of a width equal to the thickness of the radiator, said strip having transverse corrugations extending from both its sides across its full width, alternate ones of said corrugations on one side of said strip projecting beyond the intermediate corrugations to form spacing members and the remaining corrugations on both sides of strip being of substantially the same depth as each other, said strip being folded with said spacing members extending toward each other and engaging intermediate ones of said corrugations on the inside of the folded strip, said units being held together by solder, the corrugations on the side of the sheet away from said spacing members being flattened between the edge portions of the strip to form said water passages from top to bottom of the radiator between adjacent units.

2. In a radiator, the combination of a plurality of similar units assembled in reversed relation to form water passages between them, each unit comprising a strip of thin sheet metal of a width equal to the thickness of the radiator, said strip having transverse corrugations extending from both its sides across its full width, alternate ones of said corrugations on one side of said strip projecting beyond the intermediate corrugations to form spacing members and the remaining corrugations on both sides of strip being of substantially the same depth as each other, said strip being folded with said spacing members extending toward each other and engaging intermediate ones of said corrugations on the inside of the folded strip, said units being held together by solder, the corrugations forming said spacing members being of triangular cross section and the remaining corrugations being of circular cross section, the corrugations on the side of the sheet away from said spacing members being flattened between the edge portions of the strip to form said water passages from top to bottom of the radiator between adjacent units.

3. In a radiator, the combination of a plurality of similar units assembled in reversed relation to form water passages be-

tween them, each unit comprising a strip of thin sheet metal of a width equal to the thickness of the radiator, said strip having transverse corrugations extending from both its sides across its full width, alternate ones of said corrugations on one side of said strip projecting beyond the intermediate corrugations to form spacing members and the remaining corrugations on both sides 5 of strip being of substantially the same depth as each other, said strip being folded with said spacing members extending toward each other and engaging intermediate ones of said corrugations on the inside of 10 the folded strip, said units being held together by solder, the corrugations forming said spacing members being of triangular cross section and the remaining corrugations being of circular cross section, said 15 corrugations being of a form to leave vertical water passages between adjacent units, the cross section of each water passage being uninterrupted from top to bottom and smaller at each point of passing from one 20 pair of corrugations to the next pair than it is between each pair of corrugations.

4. A unit for a radiator comprising a strip of thin sheet metal having transverse corrugations extending from both its sides 30 across its full width, alternate ones of said corrugations on one side of said strip projecting beyond the intermediate corrugations to form spacing members and the remaining corrugations on both sides of said 35 strip being of substantially the same depth as each other, said strip being folded with said spacing members extending toward each other and engaging intermediate ones of said corrugations on the inside of the 40 folded strip, the corrugations on the side of the strip away from said spacing members being flattened between the edge portions of the strip toward said spacing members.

5. A unit for a radiator comprising a strip 45 of thin sheet metal having recurring series of transverse corrugations formed therein, said corrugations having the same pitch distance along said strip, and each series of corrugations consisting of a first corrugation extending from one side of the strip, a second similar corrugation extending from the other side of the strip, a third similar corrugation extending from said one side of the strip, and a fourth corrugation extending from the other side of the strip, the first three corrugations being of the same 55 depth and the fourth corrugation being deeper to form a spacing member, said strip being folded to form a unit bringing the fourth corrugations on each side into engagement with the second corrugations on the other side, the first and third corrugations of each series being flattened between the edge portions of the strip in the direction of the second and fourth corrugations without 60 change of shape of said first and third corrugations at the edge portions of the strip.

6. A unit for a radiator comprising a strip of thin sheet metal having recurring series of transverse corrugations formed therein, said corrugations having the same pitch distance along said strip, and each series of corrugations consisting of a first corrugation extending from one side of the strip, a second similar corrugation extending from the other side of the strip, a third similar corrugation extending from said one side of the strip, and a fourth corrugation extending from the other side of the strip, the first three corrugations 65 being flattened between the edge portions of the strip in the direction of the second and fourth corrugations.

without change of shape of said first and third corrugations at the edge portions of the strip.

6. A unit for a radiator comprising a strip of thin sheet metal having recurring series of transverse corrugations formed therein, said corrugations having the same pitch distance along said strip, and each series of corrugations consisting of a first corrugation extending from one side of the strip, a second similar corrugation extending from the other side of the strip, a third similar corrugation extending from said one side of the strip, and a fourth corrugation extending from the other side of the strip, the first three corrugations being of the same depth and the fourth corrugation being deeper to form a spacing member, said strip being folded to form a unit bringing the fourth corrugations on each side into engagement with the second corrugations of the other side, the first three corrugations of each series being of circular cross section and the fourth corrugation being of triangular cross section.

7. A unit for a radiator comprising a strip of thin sheet metal having recurring series of transverse corrugations formed therein, said corrugations having the same pitch distance along said strip, and each series of corrugations consisting of a first corrugation extending from one side of the strip, a second similar corrugation extending from one side of the strip, a third similar corrugation extending from said one side of the strip, and a fourth corrugation extending from the other side of the strip, the first three corrugations being of the same depth and the fourth corrugation being deeper to form a spacing member, said strip being folded to form a unit bringing the fourth corrugations on each side into engagement with the second corrugations of the other side, the first three corrugations of each series being of circular cross section and the fourth corrugation being of triangular cross section, the first and third corrugations of each series being flattened between the edge portions of the strip in the direction of the second and fourth corrugations without change of shape of said first and third corrugations at the edge portions of the strip.

8. A formed strip for making radiator units comprising a strip of thin sheet metal having recurring series of transverse corrugations formed therein, said corrugations having the same pitch distance along said strip, and each series of corrugations consisting of a first corrugation extending from one side of the strip, a second similar corrugation extending from the other side of the strip, a third similar corrugation extending from said one side of the strip, and a fourth corrugation extending from the other side of the strip, the first three corrugations being flattened between the edge portions of the strip in the direction of the second and fourth corrugations.

- being of the same depth and the fourth corrugation being deeper to form a spacing member, the first and third corrugations of each series being flattened between the edge portions of the strip in the direction of the second and fourth corrugations without change of shape of said first and third corrugations at the edge portions of the strip.
9. A formed strip for making radiator units comprising a strip of thin sheet metal having recurring series of transverse corrugations formed therein, said corrugations having the same pitch distance along said strip, and each series of corrugations consisting of a first corrugation extending from one side of the strip, a second similar corrugation extending from the other side of the strip, a third similar corrugation extending from said one side of the strip, and a fourth corrugation extending from the other side of the strip, the first three corrugations being of the same depth and the fourth corrugation being deeper to form a spacing member, the first three corrugations of each series being of circular cross section and the fourth corrugation being of triangular cross section.
10. A formed strip for making radiator units comprising a strip of thin sheet metal having recurring series of transverse corrugations formed therein, said corrugations having the same pitch distance along said strip, and each series of corrugations consisting of a first corrugation extending from one side of the strip, a second similar corrugation extending from the other side of the strip, a third similar corrugation extending from said one side of the strip, and a fourth corrugation extending from the other side of the strip, the first three corrugations being of the same depth and the fourth corrugation being deeper to form a spacing member, the first three corrugations of each series being flattened between the edge portions of the strip in the direction of the second and fourth corrugations without change of shape of said first and third corrugations at the edge portions of the strip.

10. A formed strip for making radiator

units comprising a strip of thin sheet metal having recurring series of transverse corrugations formed therein, said corrugations having the same pitch distance along said strip, and each series of corrugations consisting of a first corrugation extending from one side of the strip, a second similar corrugation extending from the other side of the strip, a third similar corrugation extending from said one side of the strip, and a fourth corrugation extending from the other side of the strip, the first three corrugations being of the same depth and the fourth corrugation being deeper to form a spacing member, the first three corrugations of each series being of circular cross section and the fourth corrugation being of triangular cross section, the first and third corrugations of each series being flattened between the edge portions of the strip in the direction of the second and fourth corrugations without change of shape of said first and third corrugations at the edge portions of the strip.

In witness whereof we hereunto subscribe our names this 18th day of August, A. D. 1919.

HARRY KAUFMAN.
SAMUEL SCIENS.
